UNITED STATES PATENT OFFICE.

GEORGE A. KNOBLOCK, OF SOUTH BEND, INDIANA, ASSIGNOR TO SOUTH BEND CHILLED PLOW COMPANY, OF SOUTH BEND, INDIANA, A CORPORATION OF INDIANA.

ADJUSTING MEANS FOR PLOW-POINTS.

1,118,023.

Specification of Letters Patent.

Patented Nov. 24, 1914.

Application filed December 6, 1913. Serial No. 804,992.

To all whom it may concern:

Be it known that I, GEORGE A. KNOBLOCK, a citizen of the United States, residing at South Bend, in the county of St. Joseph 5 and State of Indiana, have invented certain new and useful Improvements in Adjusting Means for Plow-Points, of which the following is a specification.

The invention relates generally to an improvement in adjusting means for plow points, and particularly to a means for varying the suction of said points with a view to maintaining the plowing efficiency of the implement.

15 The main object of the present invention is the provision of plow point adjusting means carried by the beam and coöperating with the standard with a view to varying the suction, or degree of angle of the plow 20 point with reference to the beam, the said means being adapted for simple operation and for convenient locking to maintain the predetermined adjustment.

The invention in the preferred form of 25 details will be described in the following specification, reference being had to the accompanying drawings, in which:—

Figure 1 is a broken elevation illustrating the application of the improvement to a 30 plow. Fig. 2 is a plan view of the same. Fig. 3 is a broken elevation, the view being taken from the side opposite that shown in Fig. 1.

In the accompanying drawings, I have 35 shown, primarily to illustrate the details of the present improvement, a plow beam 1, comprising the usual spaced sections, through which extends the standard 2 carrying the usual plow or other appropriate 40 implement 3 at its lower end. Mounted on the beam adjacent the standard is a lever A, having a latch B for engagement with the segment C to hold same in any desired position. The lower end of the lever is 45 fixed to a rotative shaft D, which latter is connected with the opposite sides of the standard by arms E, E, secured at one end to said shaft, and their free swinging ends each provided with a slot F to receive a bolt 50 G passed through the standard to provide a pivotal as well as a relatively sliding connection, and by means of which described mechanism the standard may be vertically adjusted. The details of these elements is

not important, it being understood for example, that any usual or preferred means may be employed for vertically adjusting the standard with relation to the beam, though such forms no part of the present invention.

Secured to the plow beam, between the strips or sections in the form shown, is a bracket 4, comprising a vertical arm 5 and a diagonal or inclined arm 6. The bracket is preferably constructed as an entirety and bolted in place through the medium of bolts 7. The bracket at the juncture of the arms 5 and 6 above the beam is formed to provide a head 8, and beyond the head formed to provide a notched segment 9. The head 70 is formed with an opening 10 in which is rotatably mounted a stub shaft 11 projecting laterally from one end of an operating lever 12 which, when in position, bears against one side surface of the head. A locking 75 member 13 is pivotally connected to the operating lever 12 and is formed with a slot 14 to receive a pin 16 projecting from a locking dog 17 slidably connected to the lever 12 through the medium of a pin and 80 slot connection 18. The locking lever and operating lever are formed to provide handles 19 and a spring 20 is arranged between the handles to normally maintain them spaced to seat the locking dog 17 in the 85 adjacent notch. A pair of links 21 are pivotally connected to the standard 2 on opposite sides thereof and immediately above the beam, and at their opposite ends mounted upon the bolt 7 connecting the 90 lower end of the arm 5 of the bracket to the beam. A pair of operating links 23 are pivotally connected at one end to the beam 2 on opposite sides of the latter, and above the links 21, the opposite ends of the links 23 95 being eccentrically connected at 24 to the opposite ends of the stub shaft 11.

From the above description, it will be seen that by means of the two pairs of links the usual vertical adjustment of the 100 standard may be readily performed, while by actuating the operating lever 12, and locking the same in the adjusting position the angle of the standard on which the plow point is mounted may be varied at 105 will. By this construction the plow point as it becomes dull and worn may have its angle of cut varied so that the plow will

continue to dig the same depth of furrow. The invention is particularly adapted for riding plows and seeders, though its use is contemplated with any and all structures with which it may be operatively associated.

What is claimed is:—

- 10 1. The combination with a plow beam, of a plow standard, a link pivotally connecting said beam and standard, a bracket secured to the beam, and means intermediate the bracket and standard including eccentric operating means for adjusting the inclination of the standard with relation to the beam.
- 15 2. The combination with a plow beam, of a plow standard, a link pivotally connecting the standard and beam, a bracket secured to the beam, a member rotatably mounted in the bracket, and a link pivotally connected

to the standard and eccentrically connected to said member.

- 20 3. The combination with a plow beam, of a plow standard, a link pivotally connecting the standard and beam, a bracket secured to the beam, a member rotatably mounted in the bracket, a link pivotally connected to the standard and eccentrically connected to said member, means for operating the member, and means for locking the member in adjusted position.

In testimony whereof I affix my signature 30 in presence of two witnesses.

GEORGE A. KNOBLOCK.
